UNITED STATES PATENT OFFICE.

JOHN LEWIS GRAFFLIN, OF ASTORIA, NEW YORK.

APPARATUS FOR DISTILLATION OF COAL.

1,274,033.

Specification of Letters Patent. Patented July 30, 1918.

Application filed November 20, 1917. Serial No. 203,011.

To all whom it may concern:

Be it known that I, JOHN L. GRAFFLIN, a citizen of the United States, residing at Astoria, in the county of Queens, State of New York, have invented certain new and useful Improvements in Apparatus for Distillation of Coal, of which the following is a description, reference being had to the accompanying drawings, forming a part hereof.

10 My invention relates to apparatus for dry distillation of coal and has for its object to provide an apparatus for the production from coal relatively rich in volatile hydrocarbons, of a waxy material suitable for use 15 as a lubricant and for other purposes, as well as the production of gas and the by-products usually carried off with the gas in coal distillation and subsequently recovered therefrom by washing or otherwise.

20 In the ordinary process of coal distillation it has been customary to heat the retort as highly at its lower side or bottom end as in its upper part with the purpose of producing the largest possible amount of gas and 25 volatile by-products carried by the gas cracking or breaking up the liquid or semi-liquid products of distillation by subjecting them to high heat so as to leave as little as possible of liquid or semi-liquid material in 30 the form of tar or tarry matter as possible. More or less tar is produced in coal distillation as ordinarily carried on and is objectionable both because it tends to clog the bottom of the retort and is difficult to get 35 rid of.

By the apparatus of my present invention the liquid or semi-liquid material produced in the process of distillation is separated from the mass of material being distilled and 40 is not subjected after such separation to heat sufficient to crack it or break it up into volatile matter capable of passing off with the gas, and a tarry residue, with the result that a considerable quantity is produced of a relatively soft waxy material having a low melting point without tar or tarry residue.

I obtain this product from the distillation of coal by so arranging the retort that its lowest portion to which the liquid or semi-liquid matter settles by gravity is substantially cooler than the body of the retort so that this matter when once separated from the coal is kept at a temperature below that at which cracking or the driving off of other 55 than the lighter volatile matter will take

place, and I provide means by which this liquid or semi-liquid matter may be drawn off without discharging the coke or other material remaining in the retort after the distillation is completed. By the construction of the retort bottom in the apparatus I am able to avoid the tendency of the retort bottom to warp and become distorted so as to prevent its ready removal and replacement.

With the above explained objects and other objects hereinafter explained in view my invention consists in the construction and combination of elements hereinafter set forth and particularly pointed out in the claims.

Referring to the drawings:

Figure 1 is a vertical sectional view of apparatus embodying my invention adapted to carry out my process and

Fig. 2 is a vertical sectional view of the bottom of the retort on an enlarged scale.

In the drawings 1 indicates the retort here shown as a vertical retort circular in cross section of somewhat larger diameter at its lower end than at its upper end so as to facilitate the discharge of the exhausted material. The retort has at its upper end a removable cover 2 held in closed position by the usual clamping means 3 and 40 has near its upper end an offtake pipe 21 for the gaseous products of the distillation.

The retort is supported by brick work or other supporting means so arranged as to leave a space or chamber 4 below the lower 45 end of the retort to receive the contents of the retort after the distillation is completed. The brick work or other supporting means fits closely about the lower end of the retort and extends upward closely about the retort 50 for a short distance above its lower end. Above the point at which this closely fitting brick work or other supporting means terminates, a space is left between the wall of the retort and the supporting means forming a heating passage or flue 5. At suitable intervals rings 6 extend inward to the wall of the retort these rings being provided with 55 openings 7 for the passage of the heating medium, the openings in adjacent rings being preferably out of line so that the heating medium will take a spiral course about the retort. From near the upper end of the retort a passage 8 leads to a chimney 9. A

firebox 10 serves as the source of heat, the 60 65 70 75 80 85 90 95 100 105 110

products of combustion passing from the firebox through flue 11 to the lower end of the heating passage or flue 5.

By the arrangement shown the heating medium first strikes the retort at a point some distance above the bottom, the lower end of the retort being protected by the enclosing brickwork and the bottom being in the space or chamber 4 which is not heated.

10 The bottom 12 is carried by a spider 14 hinged at 15 at one side to the lower end of the retort and removably held in position at a point opposite the hinge by a clamping screw 16 of ordinary construction. The 15 lower end of the retort as shown is provided with a groove 13 for the usual asbestos packing.

The bottom 12 is provided on its upper side with posts or projections 17 on which is 20 secured a plate 18 slightly smaller in diameter than the interior of the retort so as to leave between its edge and the retort wall sufficient space to permit liquid material to flow past the plate into the chamber space 25 between it and the bottom but not to permit the coal or other solid material to pass, this plate being also provided with perforations 19 to permit free passage of the liquid or semi-liquid material. A draw off cock 20 is 30 provided in the bottom 12 for drawing off the matter which accumulates between the plate or false bottom 18 and the bottom 12.

This plate or false bottom 18 is preferably arranged about 15 inches above the bottom. 35 This matter which accumulates between the plate 18 and the bottom is liquid while subjected to the heat of the retort and flows readily from the cock 20 but is waxy or semi-solid at ordinary temperatures melting 40 to liquid form at a low heat, becoming quite soft at 100 degrees F. and forms an excellent lubricant.

It will of course be understood that while I prefer to arrange the retort vertically as 45 shown, it may be arranged horizontally in which case the plate or false bottom 18 would extend along the lower portion of the retort and this lower portion would be protected against the direct heat of the heating

medium. It should also be understood that I do not desire to be limited to the details of construction shown particularly as regards the means for holding the cover and bottom of the retort in place as any convenient or usual means may be employed for this purpose.

Having thus described my invention what I claim is:

1. In apparatus for distilling coal the combination of a retort and means for heating the retort arranged to act thereon from a level substantially above the bottom upward, means for protecting the lower portion of the retort from direct action of the heating means, a dumping bottom for the 65 retort, and a false bottom carried by the retort bottom within the portion of the retort protected from direct action of heating means.

2. In apparatus for distilling coal the combination of a retort and means for heating the retort arranged to act thereon from a level substantially above the bottom upward, means for protecting the lower portion of the retort from direct action of the 70 heating means, a dumping bottom for the retort, a false bottom carried by the retort bottom within the portion of a retort protected from direct action of heating means and means for drawing off liquid from the 80 space between the bottom and the false bottom.

3. In apparatus for distilling coal the combination of a retort and means for heating the retort arranged to act thereon from a level substantially above the bottom upward, means for protecting the lower portion of the retort from direct action of the heating means, a dumping bottom for the retort, a perforated plate, means carried by 90 the bottom for supporting the perforated plate a substantial distance above it but within the portion of the retort protected from direct action of the heating means.

In testimony whereof I affix my signature this 20th day of November 1917.

JOHN LEWIS GRAFFLIN.
